(57) CLAIM

The ornamental design for a hooded blanket with phone pocket, as shown and described.

DESCRIPTION

FIG. 1 is a perspective view of a hooded blanket with phone pocket showing my new design;

FIG. 2 is a front view thereof;

FIG. 3 is a back view thereof;

FIG. 4 is a left view thereof;

FIG. 5 is a right view thereof;

FIG. 6 is a top plan view thereof; and,

FIG. 7 is bottom plan view thereof.

The broken lines depict portions of the hooded blanket with phone pocket and form no part of the claimed design.
